CONTAINER CAPS AND SYSTEMS

CROSS-REFERENCE TO RELATED APPLICATIONS

This application claims the benefit of U.S. Provisional Application No. 61/039,061, filed Mar. 24, 2008, the entire contents of which are incorporated by reference.

BACKGROUND OF THE INVENTION

1. Field of the Invention

The present invention relates generally to containers, and, more particularly, to container caps and systems.

2. Description of Related Art

Products are typically stored within containers. For example, cosmetic and food products are often stored in bottles and the like. A container may have a cap or lid that allows a consumer to have access to the product in a controlled fashion. When the cap is in an open position, the product is dispensed typically under an externally applied pressure and/or due to the force of gravity. When the cap is in a closed position, the product is stopped from leaving the container.

SUMMARY OF THE INVENTION

The present invention provides container caps and systems. Some embodiments of the present caps include a bottom portion having a top surface that includes a centered opening, a first recessed holding element coupled to the centered opening through a first recessed region, a second recessed holding element coupled to the centered opening through a second recessed region, and a raised element coupled to the centered opening; and a top portion couplable to the bottom portion, the top portion having a bottom surface that includes an off-centered opening, a first raised element, and a second raised element.

In some embodiments, the present caps include a top portion and a bottom portion, the top portion being couplable to the bottom portion, the top and bottom portions being configured to cause the cap to reach an open position starting from a closed position when: the top portion is rotated in a clockwise direction with respect to the bottom portion from a closed position; and the top portion is rotated in a counter-clockwise direction with respect to the bottom portion from the closed position; the top and bottom portions being configured to restrict relative rotation between them to less than 360 degrees. In some embodiments, such rotation is restricted to approximately 240 degrees. In other embodiments, such rotation is restricted to approximately 90 degrees. In still other embodiments, such rotation is restricted to approximately 60 degrees.

Some embodiments of the present container systems include a bottle configured to hold a product, and a two-piece cap coupled to the bottle. The two-piece (or two-portion) cap may include a dispensing system that includes two or more open positions and one or more closed positions.

Any embodiment of any of the present container systems and caps may consist of or consist essentially of—rather than comprise/include/contain/have—the described elements and/or features. Thus, in any of the claims, the term “consisting of” or “consisting essentially of” may be substituted for any of the open-ended linking verbs recited above, in order to change the scope of a given claim from what it would otherwise be using the open-ended linking verb.

2

Details associated with the embodiments described above and others are presented below. Other embodiments of the present caps and container systems are possible.

5 BRIEF DESCRIPTION OF THE DRAWINGS

The following drawings illustrate by way of example and not limitation. Every feature of a given structure is not always labeled in every figure in which that structure appears, in 10 order to keep the figures clear.

FIG. 1 is a perspective view of one of the present container systems that includes one of the present caps.

FIG. 2 is a partial cross-sectional view taken along lines 2-2 shown in FIG. 1.

15 FIG. 3 is an assembly view of the container system shown in FIG. 1.

FIG. 4 is a bottom view of the top portion of the cap shown in FIG. 2.

FIG. 5 is a cross-sectional view taken along 5-5 shown in 20 FIG. 4.

FIG. 6 is a top view of the bottom portion of the cap shown in FIG. 2.

FIG. 7 is a cross-sectional view taken along 7-7 shown in FIG. 6.

25 FIG. 8 is a top view of the cap shown in the preceding figures, and illustrates (via hidden lines and arrows) how the two cap portions can rotate with respect to each other.

DESCRIPTION OF ILLUSTRATIVE EMBODIMENTS

30 The term “coupled” is defined as connected, although not necessarily directly, and not necessarily mechanically. The terms “a” and “an” are defined as one or more unless this disclosure explicitly requires otherwise. The terms “substantially,” “approximately,” “about,” and variations thereof are defined as being largely but not necessarily wholly what is specified, as understood by a person of ordinary skill in the art. In one non-limiting embodiment, the term substantially 35 refers to ranges within 10%, preferably within 5%, more preferably within 1%, and most preferably within 0.5% of what is specified.

35 The terms “comprise” (and any form of comprise, such as “comprises” and “comprising”), “have” (and any form of have, such as “has” and “having”), “include” (and any form of include, such as “includes” and “including”) and “contain” (and any form of contain, such as “contains” and “containing”) are open-ended linking verbs. As a result, a cap or container system that “comprises,” “has,” “includes” or “contains” one or more elements possesses those one or more elements, but is not limited to possessing only those one or more elements. Likewise, an element of a cap that “comprises,” “has,” “includes” or “contains” one or more features possesses those one or more features, but is not limited to 40 possessing only those one or more features. For example, a cap that includes a top portion and a bottom portion that includes a centered opening, a first recessed holding element coupled to the centered opening through a first recessed region, a second recessed holding element coupled to the centered opening through a second recessed region, and a raised element coupled to the centered opening is a cap with a bottom portion that includes the specified features but is not limited to having only those features. Such a bottom portion could also include, for example, a second raised element.

45 Furthermore, a device or structure that is configured in a certain way is configured in at least that way, but it may also be configured in ways other than those specifically described.

FIG. 1 depicts container system 100. System 100 comprises cap or lid 101 operatively coupled to bottle 102. Bottle 102 may be any type of bottle, bin, can, chamber, flask, jar, jug, receptacle, repository, tube, vessel, vial, or the like. A product such as, for example, a cosmetic or food product (not shown) may be stored within bottle 102. Cap 102 allows a consumer to have access to the product in a controlled manner. Particularly, when system 100 is in an open position, the product may be dispensed, for instance, under an externally applied pressure, the force of gravity, or both. When system 100 in a closed position, the product is stopped from leaving bottle 102. Although bottle 102 is shown as having a cylindrical shape, it may have any shape.

Cap 101 allows a user to operate system 100 with the right or left hand. Particularly, cap 101 is configured with a dispensing system that includes two open positions that are on opposite rotational sides of one closed position. As a result, system 100 may assume an open position when cap 101 is turned either clockwise or counterclockwise from its closed position.

In one embodiment, cap 101 comprises top and bottom portions, discussed in more detail below with respect to FIGS. 2 and 3. In another embodiment, cap 101 comprises only a top portion and another portion equivalent to the bottom portion of FIG. 3 may be manufactured or otherwise provided as an integral part of bottle 102.

Top portion 200, which is shown in FIG. 1, and bottom portion 300 are shown in cross section in FIG. 2. Top portion 200 includes dispensing element or opening 201, which may be positioned off-center and/or near the edge of top portion 200. When system 100 is in one of its open positions, the product held within bottle 102 can exit cap 101 through opening 201. Bottle 102 may be coupled to the underside of bottom portion 300 in any suitable manner, including via a threaded engagement as shown in FIG. 2 or a snap-fit engagement. For a snap-fit engagement, the bottle and the cap (when the cap is of the two-piece configuration shown in the figures) can be provided with cooperating configurations well known to those of ordinary skill in the art for creating snap-fit engageable parts.

As shown in FIG. 3, bottom portion 300 includes surface elements on its top surface and, more specifically, on central projection 304. Bottom portion also includes restriction element 302 and rail element 303, which is female in nature. Top portion 200 includes surface elements that interact with the surface elements of bottom portion 300, as described in greater detail below. Top portion 200 also includes stop element 202 that, together with restriction element 302, controls the extent to which the two portions can rotate with respect to each other. In addition, top portion 200 includes one or more male rail elements 203 that ride in rail element 303 of bottom portion 300 and allow the portions to rotate with respect to each other; together these rail elements also serve at least in part as the mechanism that couples the depicted embodiment of top portion 200 and bottom portion 300 together.

Cap 101 may be configured such that the top and bottom portions can be coupled to each other in any suitable manner, such as through a snap fit. This may be achieved by tapering the bottom portion of male rail elements 203 (see FIG. 2 and FIG. 5) such that the top portion can fit down over the bottom portion more easily than if the male rail elements had a rectangular profile.

FIGS. 4 and 5 are bottom and cross sectional views, respectively, of top portion 200. FIG. 4 shows that the surface elements of the bottom surface of top portion 200 include first protruding or raised (e.g., convex (cx)) element 401 and second raised (e.g., convex) element 402. The surface elements

of the bottom surface also include first and second raised (e.g., convex) regions 404 and 405 that extend from elements 401 and 402, respectively, toward a central area of the bottom surface. The surface elements of the bottom surface also include region 406, which may be recessed (e.g., concave) or otherwise indented into the top portion, coupling dispensing element or opening 201 to the central area of the bottom surface.

In addition to showing one or male rail elements 203 and stop element 202, FIG. 5 shows vertical collar 204, which encircles the surface elements of top portion 200 and helps keep top portion 200 centered over bottom portion 300 by contacting central projection 304 of bottom portion 300, as shown in FIG. 2.

FIGS. 6 and 7 are top and cross sectional views, respectively, of bottom portion 300. The surface elements of the top surface of bottom portion 300 include first element 501 (also characterizable as first holding element 501), which includes a centrally oriented recessed (e.g., concave (cc)) portion 521 surrounded in part by a raised lip 531 that serves to help keep the top and bottom portions in a given open position once they get there; second element 502 (also characterizable as second holding element 502), which includes a centrally oriented recessed (e.g., concave (cc)) portion 522 surrounded in part by a raised lip 532 that serves to help keep the top and bottom portions in a given open position once they get there; central opening 507; and raised (e.g., convex (cx)) element 508. Elements 501, 502, and 508 may all be configured to fit with elements 401 and 402 and opening 201. Bottom portion 300 also includes a downwardly-projecting section that defines a passageway 509 extending from central opening 507 and perpendicular to the flat portion of the top surface of bottom portion 300. Recessed (e.g., concave) regions (e.g., channels) 504 and 505 extend from first and second holding elements 501 and 502, respectively, toward a central area of the top surface of bottom portion 300, and may be shaped or contoured to match the shape or contour of raised regions 404 and 405 of the bottom surface of top portion 200 when properly aligned with them. Center opening 507 may be coupled to raised element 508 via raised (e.g., convex) channel 506, which can be shaped to conform to recessed channel 405 of top portion 200.

As a result of the configuration of the top and bottom portions of cap 101, product exiting bottle 102 through opening 507 can flow into channel 504 or 505, depending on which is not occupied by either raised region 404 or 405. The product is then directed by that recessed channel to holding element 501 or 502. Product will be deterred from traveling on the top surface of bottom portion 300 other than through that channel (e.g., either 504 or 505) and into the holding element associated with that channel (e.g., either 501 or 502) because raised regions 404 and 405 will occupy the other of recessed channels 504 and 505 and raised region 506.

Raised region 506 may interfere with raised region 404 or 405 when they are aligned. However, the container system (and more specifically cap 101) may be configured such that there is sufficient "play" in the fit between male rail elements 203 and (female) rail element 303 that the top and bottom portions may tilt somewhat without becoming uncoupled when opposed raised regions 506 and either 404 or 405 are aligned. Alternatively, either or both of raised region 506 and raised element 508 may be configured to be biased toward a raised position (which they would occupy when aligned with recessed region 406 and opening 201, respectively) but depressable to a recessed position when contacted by raised region 404 or 405 and raised element 401 or 402, respectively. Such a configuration may be achieved in a number of different

way, such as for example through the material chosen for bottom portion **300** (if raised region **506** and raised element **508** are integral with bottom portion **300**), or through the manner in which raised region and/or raised element **508** are coupled to bottom portion **300** if they are made from separate structures (though, in such a case, bottom portion **300** still may be characterized as having or including raised region **506** and raised element **508**). Bottom portion **300** may also include a tapered base section **510** that is configured to contact to some extent an upper tapered portion of container **102**, shown in FIG. 2.

Top and bottom portions **200** and **300** are couplable to each other and, in operation, can rotate with respect to each other. More specifically, the top surface of bottom portion **300** can rotate with respect to the bottom surface of top portion **200**. However, restriction element **302** and stop element **202** are configured to interact with each other to restrict relative movement of the cap portions to less than 360 degrees. For example, bi-directional arrow **610** in FIG. 8 shows that stop element **202** and restriction element **302** may be configured such that stop element **202** is allowed to travel approximately 240 degrees before reaching one side of restriction element **302** from the other side of the restriction element. In other embodiments, the total relative travel between the two may be 120 degrees or less, 90 degrees or less, 60 degrees or less, 40 degrees or less, or any other desired amount.

The depicted embodiment of the present caps is configured such that cap **101** assumes two open positions and one closed position as the user rotates top portion **200** with respect to bottom portion **300**. Cap **101** is in an open position when opening **201** is aligned with either first holding element **501** or second holding element **502** of bottom portion **300**, thus allowing a product to exit from bottle **102** into bottom portion **300** and out through top portion **200**. Cap **101** is in a closed position when opening **201** of the top portion is aligned with raised element **508**, as shown in FIG. 8. When top portion **200** is rotated relative to bottom portion **300** in the direction of clockwise arrow **614** from the depicted closed position, opening **201** moves to a first open position over first holding element **501**, and the bottom edge (from the perspective shown in FIG. 8) of stop element **202** rests against (or may contact temporarily) the lower edge of restriction element **302**. When top portion **200** is rotated relative to bottom portion **300** in the direction of counterclockwise arrow **618** from the depicted closed position, opening **201** moves to a second open position over second holding element **502**, and the top edge of stop element **202** rests against (or may contact temporarily) the upper edge of restriction element **302**. As shown in the figures, raised element **508** may be positioned mid-way rotationally between first and second holding elements **501** and **502**.

In some embodiments, the surface elements of the two portions may be configured to make an audible sound (e.g., a "click") to indicate a particular position is reached, such as an open position or the closed position. The height of raised element **508** may be such that it breaks the plane of the bottom surface of the top portion and protrudes into opening **201** when cap **101** is in its closed position.

The present caps may be made from any of a variety of suitable materials that are well-known to those of ordinary skill in the art. The material chosen may be translucent, transparent, semi-transparent, or opaque in different embodiments.

The present caps and container systems are not intended to be limited to the particular forms disclosed. Rather, they include all modifications, equivalents, and alternatives falling within the scope of the claims. For example, while the dis-

pensing element of the top portion of the cap depicted in the figures is shown as a single opening, in other embodiments the dispensing element comprises multiple (e.g., 2 or more) smaller openings clustered together. Further, while the depicted embodiment of the present caps has been provided with one closed position flanked by two open positions, in other embodiments the surface elements of the bottom portion could be configured with another biased/depressable raised region and raised element surface element (similar to **506** and **508**), to increase the number of closed positions to two. In such a case, the surface elements of the bottom portion would be arranged in the shape of a cross. The top portion's surface elements could remain three in number, though their positions would change to a T-configuration. Moreover, the top and bottom portions of the present caps could be configured with any number of alternating open and closed positions.

As another example, the restriction and stop elements can have different configurations than those shown. For instance, multiple restriction elements that are spaced apart from each other may be used rather than a single restriction element as shown in the figures.

The claims are not to be interpreted as including means-plus- or step-plus-function limitations, unless such a limitation is explicitly recited in a given claim using the phrase(s) "means for" or "step for," respectively.

The invention claimed is:

1. A cap comprising:

a bottom portion having a top surface that includes a centered opening, a first recessed holding element coupled to the centered opening through a first recessed region, a second recessed holding element coupled to the centered opening through a second recessed region, and a raised element coupled to the centered opening; and

a top portion couplable to the bottom portion, the top portion having a bottom surface that includes an off-centered opening, a first raised element, and a second raised element,

wherein the top portion being rotatable relative to the bottom portion so that:

the off-centered opening is substantially aligned with either the first or second recessed holding element

when the cap is in an open position; and

the off-centered opening is substantially aligned with the raised element of the bottom portion when the cap is in a closed position, and

wherein the first recessed region is configured to direct a substance that has traveled through a substantially centered passageway and the centered opening into the first recessed holding element and out of the cap through the off-centered opening in the top portion when the cap is in a first open position.

2. The cap of claim 1, where the first and second recessed holding elements each includes a central recessed portion bordered at least partially by a raised lip.

3. The cap of claim 1, where the first and second raised elements of the top portion are respectively substantially aligned with a first recessed element and a second recessed element of the bottom portion when the cap is in the closed position.

4. The cap of claim 1, where the first recessed holding element, the second recessed holding element, and the raised element are separated by approximately 120 degrees with respect to a center of the top surface of the bottom portion.

5. The cap of claim 4, where the off-centered opening, the first raised element, and the second raised element are sepa-

rated by approximately 120 degrees with respect to a center of the bottom surface of the top portion.

6. The cap of claim 1, the top and bottom portions being configured to restrict relative rotation between them to approximately 240 degrees.

7. The cap of claim 1, where the second recessed region is configured to direct a substance that has traveled through the substantially centered passageway and the centered opening

into the second recessed holding element and out of the cap through the off-centered opening in the top portion when the cap is in a second open position.

5 8. The cap of claim 1, the top and bottom portions being configured with mating rail elements that facilitate their rotation with respect to each other.
